[57] **CLAIM**

The ornamental design for a tactical gunsight, as shown.

DESCRIPTION

FIG. 1 is a perspective view of a tactical gunsight showing my new design;

FIG. 2 is a side elevational view of FIG. 1;

FIG. 3 is a top plan view of FIG. 1;

FIG. 4 is a bottom view of FIG. 1;

FIG. 5 is a cross-sectional view taken along line 5—5 of FIG. 3;

FIG. 6 is a rear view of FIG. 1;

FIG. 7 is a perspective view of another embodiment of a tactical gunsight showing my new design;

FIG. 8 is a rear elevational view of FIG. 7;

FIG. 9 is a perspective view of yet another embodiment of a tactical gunsight showing my new design;

FIG. 10 is an elevational rear view of FIG. 9;

FIG. 11 is still another embodiment of a tactical gunsight showing my new design; and,

FIG. 12 is a rear elevational view of FIG. 11.

The rear views of FIGS. 7, 9, and 11, represent the second through fourth embodiments of the design with all other views being the same as that shown in the first embodiment, FIGS. 1—6.
